UNITED STATES PATENT OFFICE.

HERBERT T. NOWELL, OF BILLINGS, MONTANA, ASSIGNOR TO FREDÉRICK C. AUSTIN,
OF CHICAGO, ILLINOIS.

PROJECTILE.

1,296,310.

Specification of Letters Patent.

Patented Mar. 4, 1919.

Application filed January 28, 1918. Serial No. 214,050.

To all whom it may concern:

Be it known that I, HERBERT T. NOWELL, a citizen of the United States of America, and resident of Billings, county of Yellow-
stone, and State of Montana, have invented
5 a certain new and useful Improvement in
Projectiles, of which the following is a speci-
fication.

This invention contemplates a novel pro-
10 jectile adapted to have a whirling motion
while moving through space, and provided
with means, such as one or more propeller
blades, whereby such whirling motion is con-
verted into power to propel the projectile
15 through space, and whereby a gun is not nec-
essary for firing the projectile, the only
thing required being a machine for rotating
the projectile at high speed, preliminary to
launching it into space, and for releasing it,
20 either automatically or at will, as soon as it
has attained the speed of rotation necessary
to enable it to propel itself through the air,
as will more fully appear.

It is also an object to provide certain de-
25 tails and features of construction and combi-
nations tending to increase the efficiency
and practicability of an aerial projectile of
this particular character.

To these and other useful ends the inven-
30 tion consists in matters hereinafter set forth
and claimed.

In the accompanying drawings:—

Figure 1 is a vertical section of an aerial
35 projectile embodying the principles of the
invention, showing the same in position on
the machine by which it is rapidly rotated
to enable it to develop the speed of rotation
necessary to enable it to propel itself in the
air.

40 Fig. 2 is a plan of the projectile shown in
Fig. 1.

Fig. 3 is a fragmentary detail sectional
view on line 3—3 in Fig. 4.

45 Fig. 4 is a vertical section on line 4—4
in Fig. 3, both of these views being on a
larger scale than Figs. 1 and 2.

Fig. 5 is an enlarged detail sectional view
illustrating another form of the invention.

50 Fig. 6 is a view similar to Fig. 1, but
showing hand-operated means (instead of
the automatic means of Fig. 1) for releasing
the projectile after it has attained the de-
sired or necessary speed of rotation on the
whirling disk of the machine.

As thus illustrated, the invention com-
55 prises a ring-shaped projectile 1 of metal or
any other suitable material, preferably some-
what oval in cross-section, with sharp top
and bottom edges, and provided with a cham-
ber 2 to contain the explosive or gas or
60 other things, depending upon the particular
purpose for which the projectile is to be
employed. A transverse rod 3 is suitably
mounted on said ring, and is provided with
a pair of propeller blades 4 and 5, which lat-
65 ter have their outer ends disposed in cup-
shaped castings or brackets 6 suitably se-
cured to the ring. Each cup-shaped member
6 has a removable pin 7 against which the
adjacent propeller blade normally bears,
70 whereby the two blades are held in a hori-
zontal plane, preferably by the springs 8
which keep both blades pressed tightly
against said pins. Stops 9 limit the rotation
75 of said blades into operative position, when
said pins 7 are released or removed, thereby
rendering the propeller apparatus operative
for the purpose of propelling the projectile
through the air.

Any suitable means can be employed for
whirling the projectile to give it the neces-
80 sary speed of rotation, so that it will, when
released, be capable of propelling itself
through the air. As shown, a disk 10 is
mounted on the upper end of a shaft 11,
85 which latter may be rotated at high speed
by a motor or an engine or any other suit-
able means. The top of said disk is pro-
vided with a rim or bead 12 to engage the
lower edge of the projectile, and the disk
90 is also provided with pivoted levers 13 to
engage the recesses 14 on the inner side of
the projectile, whereby the projectile is
locked on the disk. These levers are pref-
erably pivoted at 15, between their upper
95 and lower ends, and have their lower ends
provided with weights 16 engaged by
springs 17, which latter can be regulated
by the set-screws 18, whereby the upper
100 ends of the levers 13 are firmly held in en-
gagement with the projectile. As soon as
the requisite speed of rotation is reached,
the centrifugal action of the balls 16 over-
comes the pressure of the springs 17, caus-
ing the upper ends of the levers 13 to dis-
engage the projectile. These balls 16, it will
105 be seen, are connected by wires 19, or by any
suitable means, with the pins 7, and each

ball is connected by a wire 20 with the upper end portion of the other locking lever, whereby the outward movement of the balls 16 will withdraw the pins 7, and will at the same time release the projectile. Having attained a high speed of rotation, the sudden and automatic adjustment of the propeller blades 4 and 5 into operative position (see dotted lines, Fig. 3) will raise the projectile from the whirling disk, and will carry it a distance through the air, depending upon the speed of rotation and the weight of the projectile.

It will be understood, of course, that the exploding of the projectile can be accomplished in any desired manner, by a time fuse, or by any suitable device attached thereto. In any event, though, no gun is necessary for the firing of the projectile through space, a machine which will develop sufficient power to rapidly rotate the disk 10 being all that is necessary for this purpose.

In Fig. 5, the propeller apparatus is somewhat different. In this case, each propeller blade has its outer end provided with a rigid pin 21 which rotates in a bearing 22 formed in the cup-shaped member 23, which latter is secured to the inner side wall of the projectile. The meeting ends of the two blades are supported one on the other, and pivotally held together by a rigid pin 24 on one propeller blade, which pin enters a socket 25 in the other propeller blade, so that the rod 3 previously described is not necessary.

In Fig. 6, the construction is similar to that previously described, but in this case the wires 26 which lead to the pins 7 are connected to a collar 27 on the shaft 11, so that downward movement of this collar will release said pins. For this purpose, a ring 28 having handles 29 is rotatably mounted on said collar 27, and held against rotation by a stop 30, or by any suitable means, so that after the necessary speed of rotation is attained, in the previously described manner, the handles 29 can be grasped and moved downward, thus releasing the pins 7 and thereby releasing the projectile. This is possible, it will be seen, because in this case the levers 31 which are similar to the levers 13 previously described, do not have the centrifugal balls 16 at the lower ends thereof, and hence centrifugal action does not release the projectile. The arrangement further involves, it will be seen, a connection of the upper ends of said levers 31 by wires 32 with the collar 27, whereby downward movement of this collar not only withdraws the pins 7, thus allowing the propeller blades to automatically assume their operative positions, but also disengaging the upper ends of the levers 31 from the projectile.

It will be understood, however, that the

projectile, and also the machine for launching it into space, can be constructed in any suitable or desired manner, and that the releasing of the projectile can be either automatic or by hand, depending upon the character of the use to which the invention is to be put. Furthermore, it will be seen that the ring-shaped projectile, when rotated at high speed, has the characteristics of a gyroscope, whereby it will move through space with its axis of rotation maintained at the same angle. For example, if the machine for rotating the projectile is disposed in position so that the axis of rotation is maintained at an angle of about forty-five degrees, while the projectile is acquiring speed of rotation, the gyroscopic action of the ring will then maintain this angle of the axis while the projectile is traveling through the air. In this way, the projectile can be caused to move through space with accuracy, relative to its destination, and its action or movements can be accurately judged in advance, in a manner that will be readily understood. The invention, therefore, is not limited to the exact construction shown and described.

As shown and described, the invention is an explosive shell or projectile, or an explosive bomb, but it may be used for practical purposes in other directions, and may be used as a carrier for other purposes. The shape of the ring enables it to cut through the air with less friction, and it can be made of iron or steel or any other metal, and can be filled with explosive of any suitable character, or with gas or anything else, depending upon the purpose for which it is employed. The projectile can be made of any desired size or weight, and, as previously explained, any form of motive power can be used for rotating the power shaft 11 to produce the rotation. The flying projectile thus constructed is, however, not released until it has attained the speed of rotation necessary for flight, and at that time the propeller which was previously inoperative is rendered operative. In this way, the propeller does not retard the rotation while the projectile is on the machine, and does not exert any lifting force, so that the projectile rests of its own weight on the disk of said machine. However, as soon as the propeller blades are adjusted in operative position, so as to catch the air, the projectile is then lifted by its own high speed rotation into the air, and will take its flight in the direction in which its axis is inclined.

What I claim as my invention is:—

1. As an article of manufacture, an explosive projectile adapted to be rapidly rotated, and to maintain such rotation by momentum for the period of time necessary to carry it the desired distance, and provided with one or more propeller blades to cause the flight of the projectile through the air, so that the

projectile is dependent upon said rotation for its propelling power, and having provisions to prevent any effort of the projectile to rise until the requisite speed of rotation is reached.

2. A structure as specified in claim 1, said projectile being ring-shaped, and said propeller blade or blades being disposed inside of the ring.

10 3. A structure as specified in claim 1, said projectile being ring-shaped and oval in cross-section with upper and lower sharp edges, and said propeller blade or blades extending transversely from one side of the 15 ring to the other.

4. A structure as specified in claim 1, said provisions comprising means for holding said propeller blade or blades in an inoperative condition until the required speed of 20 rotation is reached, and for then releasing said blade or blades to render the same operative to propel the projectile.

5. A structure as specified in claim 1, and means including springs to automatically 25 adjust said blade or blades to operative position as soon as the projectile has acquired the necessary speed of rotation.

6. A structure as specified in claim 1, in combination with a machine having a whirling 30 support for said projectile, devices to hold said projectile in position on said support, and means for operating said devices to release the projectile when the requisite high speed of rotation is attained, said provisions including means to prevent effective 35 operation of said blades until the projectile is released.

7. A structure as specified in claim 1, in combination with means to rotate the projectile 40 and including centrifugally operating devices to automatically release the same when the necessary speed of rotation is obtained.

8. The combination of a machine provided with a rotatable support, a projectile 45 adapted to rest on said support, devices to lock the projectile on the support, an air propeller on said projectile, which propeller is rotatable with said projectile about the axis thereof, thereby to propel the projectile through the air, means to hold 50 said propeller in inoperative condition while the projectile is being rotated on said support, means to cause the release of said propeller when the required speed of rotation is reached, and means to then automatically 55 adjust the propeller to an operative position, and for releasing the projectile from said support, whereby the projectile is released at the same time that the propeller is rendered operative.

9. As an article of manufacture, an aerial projectile adapted to be rapidly rotated, and to maintain such rotation by momentum, for 60 the period of time necessary to carry it the

desired distance, and provided with one or more propeller blades to drive the projectile through the air, so that the projectile is dependent upon said rotation for its propelling power, said projectile having means 70 for holding said propeller blade or blades in an inoperative condition until the required speed of rotation is reached, and for then releasing said blade or blades to render the same operative to propel the projectile. 75

10. As an article of manufacture, an aerial projectile adapted to be rapidly rotated, and to maintain such rotation by momentum, for the period of time necessary to carry it the desired distance, and provided with one 80 or more propeller blades to drive the projectile through the air, so that the projectile is dependent upon said rotation for its propelling power, and means including springs to automatically adjust said blade 85 or blades to operative position as soon as the projectile has acquired the necessary speed of rotation.

11. The combination of a whirling projectile having a propeller by which to propel 90 itself through the air, when rotating at high speed, power-operated means to rotate said projectile without any effort thereof to rise until it attains the requisite speed of rotation for flight, and locking devices and means to 95 operate said devices to release the projectile after the required speed of rotation is reached.

12. A structure as specified in claim 11, said projectile having instrumentalities to 100 maintain said propeller inoperative while the projectile is locked in place by said devices, and to then render said propeller operative when the projectile has attained the speed of rotation necessary for flight. 105

13. As an article of manufacture, an explosive projectile adapted to be rapidly rotated, and to maintain such rotation by momentum for the period of time necessary to carry it the desired distance, and provided 110 with one or more propeller blades to drive the projectile through the air, so that the projectile is dependent upon said rotation for its propelling power, said projectile having means for holding said propeller blade 115 or blades in an inoperative condition until the required speed of rotation is reached, and for then releasing said blade or blades to render the same operative to propel the projectile. 120

14. As an article of manufacture, an explosive projectile adapted to be rapidly rotated, and to maintain such rotation by momentum for the period of time necessary to carry it the desired distance, and provided 125 with one or more propeller blades to drive the projectile through the air, so that the projectile is dependent upon said rotation for its propelling power, and means including springs to automatically adjust said 130

blade or blades to operative position as soon as the projectile has acquired the necessary speed of rotation.

15. As an article of manufacture, an explosive projectile adapted to be rapidly rotated, and to maintain such rotation by momentum, for the period of time necessary to carry it the desired distance, and provided with one or more propeller blades to drive the projectile through the air, so that the projectile is dependent upon said rotation for its propelling power, in combination with a machine having a whirling support for said projectile, devices to hold said projectile in position on said support, and means for operating said devices to release the projectile when the requisite high speed of rotation is attained.
16. As an article of manufacture, an explosive projectile adapted to be rapidly rotated, and to maintain such rotation by momentum, for the period of time necessary to carry it the desired distance, and provided

with one or more propeller blades to drive the projectile through the air, so that the projectile is dependent upon said rotation for its propelling power, in combination with means to rotate the projectile, and centrifugally operated devices to automatically release the projectile when the necessary speed of rotation is obtained.

17. The combination of a whirling projectile having a propeller by which to propel itself through the air, when rotating at high speed, and power-operated means to rotate said projectile until it attains the requisite speed of rotation for flight, and instrumentalities to maintain said propeller inoperative before the requisite speed of rotation is acquired, and to then render said propeller operative when the projectile has attained the speed of rotation necessary for flight.

Signed by me at Chicago, Cook county, Illinois, this 14th day of January, 1918.

HERBERT T. NOWELL.
